UNITED STATES PATENT OFFICE.

JESSE FRANKLIN COOK, OF MERIDIAN, MISSISSIPPI.

APPLICATOR FOR MEDICAMENTS.

Application filed March 1, 1927. Serial No. 171,795.

The purpose of the invention is to provide a simple, cheap and effective device for the application of a medicament such as a salve or unguent to the vagina or lower 5 part of the uterus; and to provide a device which is susceptible of easy cleaning and therefore capable of being kept in a sterile condition.

With this object in view the invention 10 consists in a construction and combination of parts of which a preferred embodiment is illustrated in the accompanying drawings, wherein:

Figure 1 is a elevational view of the in- 15 vention.

Figure 2 is a longitudinal sectional view on the plane indicated by the line 2—2 of Figure 1.

Figure 3 is a transverse sectional view on 20 the plane indicated by the line 3—3 of Figure 1.

The cylinder 10 is closed at the rear end as indicated at 11 and carries a plunger 12 with which is connected a plunger rod 13 25 having a slide bearing in the closed end 11. A ring 14 is carried at the outer end of the plunger rod and constitutes a finger grip by means of which the rod and the plunger may be actuated.

The forward end of the cylinder is dia- 30 metrically reduced to provide a shoulder 15, the reduced portion being externally threaded as at 16 for engagement with interior threads formed in one end of the cap 17, 35 the latter when connected with the cylinder seating against the shoulder 15. The remote end of the cap is provided with a dis- charge opening 18.

In charging the device, the plunger is 40 withdrawn to the closed end of the cylinder,

the cap 17 having been disconnected, and the medicament inserted in the cylinder. After the latter has been fully charged, the cap is reattached and the device then inserted in the affected part, so that the medicament 45 may be discharged through the opening 18 by the application of pressure on the plunger, such as is afforded by the insertion of the thumb through the ring 14 when the cylinder is grasped between the first and second 50 fingers.

The cylinder and cap are made preferably 55 of hard rubber and the cap being detachable, both it and the cylinder are accessible interiorly for cleaning.

The rod 13 is of a length that will permit 60 the plunger to be forced into the cap when the latter is attached. Therefore, the plunger may be forced out of the cylinder when the cap is detached, thus making it possible 65 to thoroughly clean the plunger.

The invention having been described, what 70 is claimed as new and useful is:

An applicator for medicaments comprising a cylinder closed at one end, a plunger 65 slidably mounted in the cylinder and having an actuating rod passing slidably through said closed end and terminating exteriorly thereof in a finger ring, and a cap detachably connected at the remote end of the cyl- 70 inder and constituting a closure therefor, the cap having a discharge opening communicating with a bore corresponding to the bore of the cylinder, the actuating rod being of a length to project the plunger beyond 75 the cylinder when the cap is detached.

In testimony whereof he affixes his sig- 80 nature.

JESSE FRANKLIN COOK,
